UNITED STATES PATENT OFFICE

128,778

DESIGN FOR A DISPLAY STAND

John Gerber, Kearney, Nebr.

Application July 5, 1940, Serial No. 93,449

Term of patent 7 years

To all whom it may concern:

Be it known that I, John Gerber, a citizen of the United States, residing at Kearney, in the county of Buffalo and State of Nebraska, have invented a new, original, and ornamental Design for a Display Stand, of which the following is a specification, reference being had to the accompanying drawing, forming part thereof.

on a reduced scale.

I claim:

The ornamental design for a display stand, as shown.

JOHN GERBER.
